BOWLING PIN ELEVATING AND RESETTING
MECHANISM

Earl G. Strong, Milan, Ohio

Application February 9, 1949, Serial No. 75,432

4 Claims. (Cl. 273—44)

1

This invention relates to bowling pin elevating and re-setting mechanisms for bowling alleys, and has more particular reference to an improved mechanism whereby each bowling pin may be set and retained in a lowered operative position and automatically tripped and raised to an inoperative position out of the path of bowling balls rolled down the alley upon being struck by a previously rolled ball.

The present invention specifically relates to improvements upon the type of bowling pin elevating and re-setting mechanism shown in my U. S. Letters Patent No. 2,207,643, dated July 9, 1940.

The primary object of the present invention is to provide a mechanism of the above kind which is very free or sensitive in action, so as to insure efficient operation.

Another object is to provide means whereby the bowling pin will be substantially vertically disposed when in both lowered operative position and raised inoperative position.

Still another object is to provide a mechanism of the above kind which is simple and durable in construction, and which is composed of parts that are easy and economical to manufacture and assemble.

The exact nature of the present invention, as well as more specific objects and features thereof, will become apparent from the following description when considered in connection with the accompanying drawing, in which:

Figure 1 is a fragmentary top plan view of a supporting frame provided with bowling pin elevating and re-setting mechanisms constructed in accordance with the present invention, the bowling pins being in lowered operative position;

Figure 2 is a side elevational view of the construction shown in Figure 1, with one of the bowling pins in raised inoperative position;

Figure 3 is an enlarged fragmentary vertical section, partly broken away, showing one of the bowling pin elevating and re-setting mechanisms mainly in side elevation, with the bowling pin illustrated in lowered operative or set position by full lines and in raised inoperative position by dotted lines;

Figure 4 is a fragmentary view, partly in front elevation and partly in section, of the construction shown in Figure 3;

Figure 5 is a horizontal section taken on the line 5—5 of Figure 4;

Figure 6 is a view similar to Figure 5 showing the position of parts immediately before the upper section of the bowling pin rod is moved to position the pivotal connection between the same

2

and the plunger rearwardly past dead center to retain the bowling pin in lowered operative or set position.

Referring in detail to the drawings, A indicates an elevated horizontal supporting frame composed of substantially similar upper and lower sections 5 and 6 rigidly connected as at 7 in spaced parallel relation, and respectively composed of rearwardly diverging angle iron side members 8 and 9 rigidly connected by spaced transverse angle iron bars 10 and 11 disposed in parallel relation. The bars 10 and 11 are arranged in pairs, one above the other, and each pair thereof carries one or more bowling pin elevating and re-setting mechanisms. As these mechanisms are alike, description of one will suffice.

As shown more clearly in Figures 3 to 6 inclusive, each mechanism includes a bowling pin rod composed of an upper section 12 having a socket 13 rigidly secured on its lower end, and a lower section 14 having its upper end pivoted at 15 within said socket to freely swing forwardly and rearwardly. The socket 13 is cut away at the front as at 16 so as to define a rear lip 17 which limits rearward movement of section 14 to a point wherein the latter is nearly aligned with the section 12, but permits said section 14 to remain vertical by assuming an angular relation to the section 12 when the latter is swung rearwardly and upwardly to a nearly horizontal rearwardly inclined position as shown in Figures 2 and 3. The lower portion of rod section 14 extends through a bowling pin 18 which is suitably secured thereon. The bar 11 has a wide slot 19 in and opening through the front edge of its horizontal flange, and disposed within the slot is the ring member 20 of a universal joint. The upper portion of rod section 12 extends freely through and is mounted in the ring member 20 upon a pin 21 for limited lateral swinging and forward and rearward sliding movements. The ring member 20 is pivotally mounted on bar 11 by means of pins 22 engaged in bearing blocks 23 bolted at 24 to the horizontal flange of bar 11 at opposite sides of slot 19, so as to permit forward and rearward swinging of rod section 12. Below the universal joint, the rod section 12 extends through the slot 25 of an angular guide and stop bracket 26 secured to the bar 11, and said slot increases in width from its ends to its intermediate portion, as shown in Figure 4.

The upper end of rod section 12 is loosely pivoted at 27 in a forked plunger head 28 provided on the lower end of a stem 29 which slidably extends through a collar 30 pivotally mounted within an open slot 31 provided in the horizontal

flange of bar 10. As shown, the collar is mounted by pivot pins 32 engaged in bearing blocks 33 bolted at 34 on the horizontal flange of bar 10, so as to permit forward and rearward swinging of plunger 28, 29. A helical compression spring 35 surrounds the stem 29 between the head 28 and the collar 30, and acts to yieldingly force the plunger downwardly. The upper end of rod section 12 has limited lateral sliding movement on the pivot at 27, and the bearing blocks 23 and 33 are adjustable to secure proper alignment and working of the parts. The arrangement is such that when the member 37 is pulled rearwardly, the rod section 12 is swung downwardly and forwardly from the dotted line position of Figure 3 to a vertical position, at which time said rod section 12 is aligned with the pivot at 27 and the stem 29 and is engaged with the bracket 26 at the lower end of slot 25. Thus, if the pull on member 37 is continued, the upper end of rod section 12 is moved slightly rearward from the vertical position and caused to slide rearwardly on the pin 21 from the position of Figure 6 to that of Figure 5, the rod section 12 rocking on the bracket 26 at the lower end of slot 25 so as to cause the pivot at 27 to move rearwardly past dead center as shown by full lines in Figure 3. Due to the downward pressure of spring 35, the rod section 12 is held in this position with the bowling pin 18 set in a vertical lowered position upon the floor of the bowling alley. When the rod section 12 is swung forwardly, it is centered laterally by the tapered form of the lower portion of slot 25, and the rod section 14 gravitates to remain in a vertical position so as to be contacted by lip 17. Should the set pin 18 be struck by a bowling ball, the rod sections 12 and 14 will be swung rearwardly and upwardly as a unit, due to engagement of rod section 14 with lip 17, until the pivot at 27 is moved forwardly past dead center. The spring 35 will then quickly force the plunger 28, 29 downwardly to accelerate the rearward and upward movement of rod section 12 and quickly elevate the pin 18 to an inoperative position above the path of any bowling balls subsequently rolled down the alley. The pivot pins 22 are movable in bearing blocks 23 to allow lateral movement of ring member 20, and due to the tilting movement of rod section 12 on pin 21 and its lateral movement on the pivot 27, the bowling pin 18 is allowed limited lateral movement that permits it to strike neighboring bowling pins as the rod section 12 swings up to the wider portion of slot 25. As the rod section 12 continues to swing upwardly, it is centered laterally by the upper part of slot 25. When the bowling ball passes the pin 18, the latter and rod section 14 gravitate to the vertical raised position shown in Figures 2 and 3, in angular relation to rod section 12. Downward movement of the plunger stem 29 is limited by engagement of rod section 12 with bracket 26 at the top of slot 25, at which time the pin 18 has been elevated out of the path of bowling balls rolled down the alley. A loop 37 is connected to the ends of pivot 27 and adapted for connection with means for simultaneously resetting all of the raised bowling pins, as generally disclosed in my above mentioned patent.

From the foregoing description, it is believed that the construction, operation and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. In combination with a bowling alley, a supporting frame mounted above the pin bed of the alley, said frame including spaced upper and lower transverse bars, a bowling pin rod composed of an upper rod section, a socket secured on the lower end of said upper rod section and having a rear depending lip, and a lower rod section having its upper end pivoted in said socket to freely swing forwardly and rearwardly from and to said lip, a bowling pin secured on the lower portion of said lower rod section, a ring member pivoted on the lower bar to tilt about a horizontal axis transverse to the alley, the upper portion of the lower rod section extending through said ring member and mounted in the latter for lateral swinging and forward and rearward sliding movements, a collar pivoted on the upper bar to tilt about a horizontal axis transverse to the alley, a plunger including a stem slideable through said collar and a forked head on the lower end of said stem having the upper end of the upper rod section pivoted therein upon a transverse axis, a helical compression spring disposed on the stem between the collar and the plunger head and acting to force the plunger downwardly and swing the upper rod section to raise the bowling pin to an inoperative position when the pivotal connection between the upper rod section and the plunger head is moved forwardly past dead center and to retain the rod and pin in a vertical lowered position when said pivotal connection is moved rearwardly past dead center, and a slotted guide and stop bracket carried by the lower bar and having the upper rod section passing therethrough below the ring member, the lower end wall of the slot of said bracket acting as a fulcrum about which the upper rod section rocks to slide the upper end of the same rearwardly relative to the ring member as said pivotal connection moves rearwardly past dead center.

2. The combination defined in claim 1, wherein said bars have horizontal flanges provided with slots within which the ring member and collar are disposed, the pivotal mounting of the ring member and collar including bearing blocks adjustably mounted on said flanges at opposite sides of said slots, and pivot pins carried by the ring member and collar and engaged in said bearing blocks.

3. The combination defined in claim 1, in combination with a member connected to said pivotal connection and operable to move the latter rearwardly past dead center.

4. The combination defined in claim 1, wherein the upper end of the upper rod section is mounted in the plunger head for movement laterally of the plunger head, and wherein the slot of said guide bracket is tapered to its ends and of a width between its ends to allow lateral swinging of said upper rod section as it swings rearwardly and upwardly to raise the bowling pin.
